UNITED STATES PATENT OFFICE.

HENRY P. COPE, OF DETROIT, MICHIGAN.

DESIGN FOR A CASING FOR SIPHON-DISCHARGE VALVES.

SPECIFICATION forming part of Design No. 25,100, dated January 28, 1896.

Application filed October 15, 1895. Serial No. 565,801. Term of patent 7 years.

To all whom it may concern:

Be it known that I, HENRY P. COPE, of Detroit, in the county of Wayne and State of Michigan, have invented a new and useful 5 Design for a Casing for a Siphon-Discharge Valve, of which the following is a specification.

My invention relates to a new and useful design for a casing for siphon-discharge valves, 10 and is illustrated in the accompanying drawings, wherein—

Figure 1 is an elevation, and Fig. 2 a cross-section on line $x-x$ thereof.

The two sides, A and B, of the valve-casing 15 are made to have the appearance of two vertical pipes joined together by an arched crown, as shown at C, and by a depression in the center, as shown at D. The lower end of the part A is curved to the left and downward, 20 as shown at F, and the lower end of the part B is also curved to the left and downward,

but not quite so much as the part F, curving down more abruptly than the part F and terminating in a recessed molding H. On the crown C and slightly to the left of the apparent center of the valve is formed a lug G.

This design presents a very pleasing appearance because of the graceful lines and curves therein, the essential feature of said design in a casing of siphon-discharge valves 30 presenting the double-pipe appearance and the outward and downward curves at the bottom of the parts A and B.

What I claim as my invention, and desire to secure by Letters Patent, is—

The design for a casing for siphon-discharge valves herein shown and described.

HENRY P. COPE.
